J. CALCO.
DETACHABLE CUFF.
APPLICATION FILED JULY 15, 1920.

1,413,897.

Patented Apr. 25, 1922.

UNITED STATES PATENT OFFICE.

JOSEPH CALCO, OF CHICAGO, ILLINOIS.

DETACHABLE CUFF.

1,413,897.

Specification of Letters Patent. Patented Apr. 25, 1922.

Application filed July 15, 1920. Serial No. 396,353.

To all whom it may concern:

Be it known that I, JOSEPH CALCO, a citizen of the United States, residing at Chicago, in the county of Cook and State of Illinois, have invented certain new and useful Improvements in Detachable Cuffs, of which the following is a specification.

This invention relates to cuffs, and the primary object of the invention is to provide an improved detachable soft cuff for men's shirts in lieu of the ordinary permanently attached cuff now used on shirts, so that the cuff can be readily removed and laundered independent of the shirt and replaced by a clean cuff when soiled, thereby eliminating the necessity of laundering the whole shirt when only the cuffs thereof are soiled. It is a well known fact that the cuffs and collars of shirts become soiled much quicker than the body portions thereof and collars are already made detachable and laundered independent of the shirt and it is now contemplated of making the soft cuffs removable so that the life of the shirt will be further enhanced.

Another prime object of this invention is to provide an improved means for connecting the detachable cuff to the shirt sleeve wrist band in such a manner that the cuff can be quickly and easily attached to or removed from the shirt, the cuff also being formed in such a manner that the attachment elements utilized for holding the cuff in position will be completely hidden from view when the cuff is worn, the fastening elements being removably associated with the cuff and wrist band so as not to interfere with the laundering of the shirt or the cuff.

A further object of the invention is to provide an improved removable soft cuff which can be reversed when one surface thereof becomes soiled, the cuff being so formed that the folded portion thereof will always be disposed outermost irrespective of the position of the same on the shirt sleeve, thereby preventing persons from telling whether the cuff has been reversed or not.

A still further object of the invention is to provide an improved shirt attachment of the above character which will be durable in use, one that is simple and easy to manufacture, and one which can be placed upon the market at a reasonable cost.

With these and other objects in view, the invention consists in the novel construc-

tion, arrangement and formation of parts as will be hereinafter more specifically described, claimed and illustrated in the accompanying drawings forming a part of this specification, in which drawings:

Figure 1 is a perspective view showing the improved cuff in position on a sleeve.

Figure 2 is a perspective view of the cuff showing the same in its open position ready to be attached to a shirt sleeve.

Figure 3 is a perspective view of the free end of a shirt sleeve, showing the means of forming the wrist band so as to facilitate the positioning thereof in engagement with the cuff, and

Figure 4 is an enlarged fragmentary sectional view through the cuff and shirt sleeve, illustrating the detachable two part cuff button utilized for holding the cuff in position on the sleeve.

Referring to the drawings in detail, wherein similar reference characters designate corresponding parts throughout the several views, the letter A generally indicates the improved cuff and B the shirt sleeve.

The cuff A is of the soft type and of the folded or turned over variety and includes a body portion 5 formed of a pair of sections, the marginal edges of which are stitched together to form the cuff and a fabric filler may be inserted between the two pieces of fabric. The upper edge of the body 5 is provided at a point spaced from the inner edge with a row of stitching 6 which extends arcuately from one transverse edge to the other, and forms a pair of independent inner flaps 7 and 8. The inner edges of the fabric at this point may be folded back and stitched to the body as at 9 so as to stiffen the flaps 7 and 8. The terminals of the flaps 7 and 8 are adapted to be detachably fastened together by fasteners 10, which will be hereinafter more specifically described and when these fasteners are in position a pocket 11 will be formed for the reception of the wrist band 12 carried by the free end of the shirt sleeve B. The side edges of the flaps 7 and 8 are provided with

aligned button holes 13 and these button holes 13 are adapted to align with button holes 14 formed in the shirt band 12 adjacent to its terminals. The inner face of the flap 7 at a point intermediate the ends thereof carries a button 15 and this button 15 is in direct alignment with a centrally

disposed button hole 16 formed in the central portion of the flap 8. The button hole 16 is adapted to register with a button hole 17 formed in the central portion of the wrist band 12.

The shirt sleeve B is of the usual construction with the exception of the wrist band 12 which is formed relatively narrow and has its outer edge curved arcuately as 10 at 18 so as to conform to the configuration of the flaps 7 and 8. This formation defines a leading forward edge, which facilitates the positioning of the wrist band in the pocket 11 of the cuff.

15 The folded portion 19 of the cuff A is formed relatively wider than the other portion thereof so as to completely overlie the flaps 7 and 8 and thereby completely hide the same from view and the folded or turned 20 over portion of the cuff 19 and the other portion of the cuff is provided with the usual aligned button holes 20 for the reception of the ordinary or any preferred type of cuff button, (not shown).

25 When the cuff is placed in position, the flaps 7 and 8 are opened as shown in Figure 2 of the drawings, and the wrist band 12 is inserted between the same. The button 15 is then placed through the button holes 17 and 16 and the fastening elements 10 are then inserted through the aligned button holes 13 and 14.

The fastening elements 10 can be of any construction, but it is preferred that the same 35 be of the two part cuff button type and as shown the same includes the male portion 21 and the resilient female portion 22. It thus can be seen that these retaining elements are freely removable from the cuff and sleeve, 40 so that the same will not interfere with the laundering of the shirt or cuffs.

From the foregoing description it can be seen that an improved detachable cuff has been provided for shirts which can be easily 45 and quickly placed in position and permit of a clean cuff to be substituted when the original cuff has been formed. The construction of the cuff is such that the position thereof can be reversed so as to bring a clean 50 surface to view when one surface thereof has been soiled. This construction also permits of the folded portion being always turned

outermost so as to prevent the fact that the cuff has been turned from becoming known. Where it is desired to reverse the position 55 of the cuff so as to bring a new surface to view the cuff is removed from the shirt and the folded portion thereof is turned back upon the other side of the cuff body and the cuff is then placed on the shirt sleeve in the 60 same manner as followed out in the preceding time.

Changes in details may be made without departing from the spirit or scope of this 65 invention; but,

I claim:

1. The combination with a shirt sleeve having a wrist band provided with an arcuate outer edge, the wrist band having button holes formed therein at spaced points, 70 of a removable cuff therefor including a body portion, and independent flaps formed on the inner edge of the body portion, the intermediate portions of the flaps being formed relatively wider than the terminals, the terminals of the flaps having aligned button 75 holes arranged to align with certain of the button holes formed in the wrist band, one of the flaps having an intermediate button hole arranged to align with certain other button holes formed in the wrist band, and a button carried by the inner surface of the other flap and arranged to engage in the last mentioned button hole, and removable fastening elements arranged to extend 80 through the aligned button holes formed in the terminals of the cuff and wrist band.

2. The combination with a shirt sleeve having a wrist band formed relatively wider at its intermediate portion than at its ends 90 to define a leading arcuate edge, of a removable soft cuff therefor including a body portion and flaps formed on the inner edge of the body portion, the flaps defining a pocket for the reception of the wrist band, the intermediate portion of the pocket being formed relatively deeper than at its ends, 95 said arcuate leading edge of the wrist band forming means for facilitating the positioning of the wrist band in said pocket, and means for detachably securing the cuff to 100 said wrist band.

JOSEPH CALCO.
